Primary Examiner — Mary Shannon Malley*Assistant Examiner* — Eric Eldone Tormanen(74) *Attorney, Agent, or Firm* — Robert Z. Evora, Esq.(57) **CLAIM**

The ornamental design for a nipple shield, as shown and described.

DESCRIPTION

FIG. 1 is an upper perspective front view of a first embodiment of a nipple shield showing our new design;

FIG. 2 is an upper perspective rear view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is an upper perspective front view of a second embodiment of the nipple shield;

FIG. 10 is an upper perspective rear view thereof;

FIG. 11 is a front view thereof;

FIG. 12 is a rear view thereof;

FIG. 13 is a top view thereof; and,

FIG. 14 is a bottom view thereof.

The broken lines in the drawings depict portions of the nipple shield that form no part of the claimed design.

1 Claim, 14 Drawing Sheets(56)
